COACH FOR PICK-UP TRUCKS

Steve J. De Gennaro, Anaheim, and Steve P. De Gennaro and John E. De Gennaro, Riverside, Calif.

Application July 19, 1957, Serial No. 47,005

Term of patent 14 years

(Cl. D14—3)

FIG. 1.

The broken line disclosure of a pick-up truck is for purposes of illustration only.

We claim:

The ornamental design for a coach for pick-up trucks, substantially as shown and described.
